UNITED STATES PATENT OFFICE.

RUDOLF von FROMMER, OF BUDAPEST, HUNGARY.

AUTOMATIC FIREARM.

Application filed April 26, 1924, Serial No. 709,202, and in Austria May 29, 1923.

In the application filed August 25, 1921, Serial Number 495,179, an automatic firearm is described that may be taken apart with great ease and rapidity and is provided with 5 a pull-off mechanism containing a hammer in which the connection between the slide and the breech-block is established by a cap with or without a helmet-like extension, whereby two types of firearms can be provided, i. e. such with an external hammer, or such with a hammer hidden within the helmet-like extension that is a so called "hammerless-piston."

Now I have ascertained that by suitably 15 shaping the cap enclosing the hammer the same can be used not only in connection with the firearm described in the application above referred to, but also in connection with other firearms provided with an external hammer, whereby a further development 20 of the progress of art described in the patent above referred to, of manufacturing two types of firearms with one and the same plant is attained, any types of firearms with 25 external hammer being enabled by the cap according to my present invention to be converted into a "hammerless" one by mere putting on of the cap.

The cap described in my patent aboved 30 referred to formed an integral part of the weapon without which the firearm would not be complete; whilst the cap according to this invention does not form an absolutely necessary part of the weapon but is only intended to change a hammer-pistol into a hammerless one.

The cap enclosing the hammer may be connected with the weapon in a number of different ways, i. e., by screw threads, pressing, or screwing up, etc.

In the accompanying drawing one form of the cap embodying the present invention is shown by way of example in connection with a firearm of usual type.

Fig. 1 is a side view of one part of a 45 firearm having a pull-off mechanism containing a hammer;

Fig. 2 is a side view of the cap;

Fig. 3 shows the cap in connection with 50 the firearm shown in Fig. 1,

Fig. 4 is a sectional view of the same taken on line α — α of Fig. 3.

The breech-slide 1 is provided with recesses 2 as usual for facilitating the grasping of the same. Corresponding recesses 55 and edges 4, 5 are formed in the inside of the cap fitting in recesses 2, in such a manner that when putting the cap 3 on the end of the breech-slide showing the recesses and sliding it downward (Fig. 3), a firm connection between the breech-slide 1 and cap 3 is attained, and the hammer is completely hidden within the cap, whereby the hammer-pistol is changed into a so called hammerless one. The outside of the cap is also 60 provided with recesses to render the handling of the breech-slide easier.

The securing of the cap 3 on the breech-slide 1 is effected in the example shown by a catch 8 subject to the pressure of spiral-spring 7. The catch 8 enters the bore 9 of the cap, and thus prevents the same to be unintentionally disengaged from the breech-slide.

Claims:

1. As a new article of manufacture, a cap open at its front side and at its bottom, adapted to be fastened on the breech of a firearm having an external hammer for completely hiding the hammer of the weapon 80 and having an outline similar to the breech of a hammerless firearm, thereby giving the weapon the outside form of a hammerless weapon and provided on its inner surface with recesses and edges to fit in the recess of 85 the breech of a weapon, enabling the cap to be slid athwart the breech for concealing the external hammer of the weapon.

2. As a new article of manufacture, a cap open at its front side and at its bottom, 90 adapted to be fastened on the breech of a firearm having an external hammer for completely hiding the hammer of the weapon and having an outline similar to the breech of a hammerless firearm, thereby giving the weapon the outside form of a hammerless weapon and provided interiorly with a recess capable of receiving a spring bolt of 95 the breech of the weapon and concealing the external hammer of the weapon.

100

3. As a new article of manufacture, an inverted channel shaped cap adapted to be attached to a firearm for concealing the hammer of the latter, the inner surfaces of the 5 sides of the cap being provided with corrugations adapted to cooperate with complementary corrugations on the breech of a weapon, said cap having a recess to receive a fastening bolt on the weapon, said cap also having an aperture adjacent the recess to permit said bolt to be actuated.
- In testimony whereof I have signed my name to this specification.

RUDOLF von FROMMER.
